COMBINATION VANITY AND CIGARETTE CASE

Charles J. Hannings, Elgin, Ill., assignor to Illinois Watch Case Company, Elgin, Ill., a corporation of Illinois

Application August 29, 1936, Serial No. 98,535

5 Claims. (Cl. 206—38)

This invention relates to a case for a pocket or pocketbook having therein multiple compartments, each covered by a lid of its own, there being also a cover for the case in its entirety. In such a construction the lids and cover may be releasably secured in closed position by appropriate catches. The present improvements are directed in part to certain special features of one such catch which combines integrally in its own structure a hook, hinge joint and spring. In addition, I have also incorporated in the present case other minor features as will hereinafter appear from the description and claims, and from the accompanying drawing wherein:

15 Figure 1 is a view in perspective of the case with covers open to exhibit the interior construction; Fig. 2 is a longitudinal section through the case taken on line 2—2 of Fig. 1; and

20 Fig. 3 is a detail in perspective of a special catch construction employed for releasably securing one of the lids in closed position.

As herein shown, the case comprises a dished body B having along one edge a series of joints 4 interfitting with other joints 5 formed along one 25 edge of a dished cover C, a pin being extended through all of the joints to hingedly connect the cover to the body. Also interfitting with the joints 4 and 5 are other joints 6 formed on one edge of a lid 7 against which presses one end of a 30 spring 8 which is coiled around the pin. The opposite pin end may bear against the body, thus exerting opposing forces on the body and lid by which the one tends to swing away from the other. In such a movement the lid also pushes 35 against the cover whereby to cause that element to swing away from the body.

The interior of the case may be arranged according to any desired plan. As shown, I have located at one end of the body a rectangular frame 9 with depending marginal flanges, three of which lie close to marginal edges of the body to which the frame may be secured with cooperation from the hinge joints and lips 10 which are inwardly extended from the body edges. 40 Formed within the frame is a sunken panel 11 defining a powder compartment. Over this compartment is positioned a lid 12 shallowly recessed to provide a rouge compartment which may be covered by a small hinged lid 13 having a suitable catch by which it is normally held closed. The compartment lid is itself joined to the frame by a hinge connection 14 along the frame side which is remote from the body end at which point I provide a spring catch 15 adapted to engage 45 the swinging edge of the lid whereby to hold it

normally closed. The frame and associated parts constitute the vanity unit the construction and arrangement of which may be variously made.

The remainder of the case is available for the accommodation of other articles, such as cigarettes, and will accordingly be referred to as the cigarette compartment. The lid 7 for this compartment is suitably dished to cooperate with the body in providing a space of ample capacity, and with the cover in the occupation of a minimum of 5 space. The end of this lid which lies proximate to the powder compartment is formed with a flange 16 having a beveled inset 17 (see Fig. 2) extending for a short distance in its central region. This inset lies opposite a catch A which, 10 as best shown in Fig. 3, is formed at one end with a beveled head 19 formed with a nose 20 which is adapted to overlie the lid 7 when the latter is moved to closed position; the catch extends away laterally through a neck portion 21, and is provided with a pair of shoulder joints 22 separated 15 sufficiently for the protrusion therethrough of a body 23 which depends a short distance and then extends laterally as at 24 to provide a bowed leaf spring 25. The hinged points of this catch lie in 20 a pocket 26 in the top of the frame 9 so as to be traversed by the pin which is comprised in the hinged connection 14 for the lid 12. The bowed spring 25 extends transversely of the case along 25 a partition wall 27 which depends from the rectangular frame 9, the spring bearing with pressure against this wall to urge the catch to the engaging position which is shown clearly in Fig. 2. The head of this catch which remains protruded above the lid 7 may be engaged by one's 30 finger to swing the catch back against the tension of its spring tongue 25 whereby the lid is released for opening movement which takes place in response to tension of the spring 8.

In use, the cover may be closed down upon 40 the body of the case, and in this movement the cigarette compartment lid is also pushed to closed position. In executing this movement the beveled inset of the lid rides down over the head of the catch until it is engaged by the nose of the latter so as to be locked down in closed position. The cover is itself provided with a lip 28 extending inwardly from its free edge for engagement by a spring catch 29 which is carried by the body, 45 there being an actuating lug 30 extending therethrough whereby the catch may be operated from the exterior of the case. To open the cover the catch 29 is pressed in, whereupon the lip 28 is disengaged. The cover may be provided with 50 55

an opening spring 31 of its own so that it will move to wide open position once the catch 29 be released. The lid 1, however, will remain closed unless the catch A is operated. Once the 5 lid is released for opening movement its spring 8 will swing the lid around to open position carrying with it, if need be, the cover C until a limit point is reached.

I claim:

- 10 1. A case including a two-compartment body to which is hinged a lid fitting over one compartment and a cover overlying the lid, a partition wall for the case compartments, and a one-piece spring catch having a pivotal mounting 15 adjacent the partition wall and bearing yieldingly thereagainst adapted to releasably engage the lid when in closed position.
2. A case in which is mounted a recessed frame 20 providing a separate compartment, a wall extended from the frame forming a partition which separates the compartment from the remainder of the case interior, a lid hinged over a portion of the case interior adjacent the compartment, and a one-piece spring catch pivotally mounted 25 on the frame resiliently bearing against the par-

tion wall and adapted to releasably engage the lid when in closed position.

3. In a case the combination of a body, a frame fitted into the body forming a compartment therein separate from the remainder of the body, 5 the frame comprising a partition wall and a spring catch pivoted to the frame and engaging with said wall, and a lid within the body releasably engaged by the catch when in closed position.

4. As a new article of manufacture, a one-piece spring catch comprising a head on which is formed a locking shoulder, a neck extended laterally from the head, a pair of aligned spaced joints depending from the neck, and a body extending from the neck between the joints and then laterally through an elongated bow to provide a leaf spring for the catch. 10 15

5. As a new article of manufacture, a one-piece spring catch comprising a locking head, a pair 20 of aligned spaced joints below the head, and a body extending between the joints and laterally through an elongated bow to provide a leaf spring for the catch. 25

CHARLES J. HANNINGS. 25
